MOLD FOR MAKING SOAP

David J. Barnes, 8660 Brittany Drive, Cincinnati, Ohio

Filed Oct. 27, 1959, Ser. No. 58,089

Term of patent 14 years

(Cl. D4—3)

Fig. 5.

Fig. 6.

Fig. 7.

Figure 1 is a side elevational view of a mold for making soap, embodying my new design, with the jaws shown in open position.

Figure 2 is a side elevational view thereof showing the jaws in closed position.

Figure 3 is a top plan view thereof.

Figure 4 is a transverse sectional view.

Figure 5 is a bottom perspective view thereof.

Figure 6 is an elevational view of one end thereof.

Figure 7 is an elevational view of the other end thereof.

The ribbon shown in broken lines is for illustrative purposes only.

I claim:

The ornamental design for a mold for making soap, as shown and described.
